US00D995151S

(12) United States Design Patent (10) Patent No.: US D995,151 S
Liu (45) Date of Patent: * Aug. 15, 2023

(54) WALLMOUNTED SHELF

(71) Applicant: Jian Liu, Guangzhou (CN)

(72) Inventor: Jian Liu, Guangdong (CN)

() Term: 15 Years

(21) Appl. No.: 35/515,504

(22) Filed: Oct. 21, 2022

(80) Hague Agreement Data

Int. Filing Date: Oct. 21, 2022

Int. Reg. No.: DM/224407

Int. Reg. Date: Oct. 21, 2022

Int. Reg. Pub. Date: Nov. 4, 2022

(51) LOC (14) Cl. 08-08

(52) U.S. Cl.

USPC D6/567

(58) Field of Classification Search

USPC D6/549, 553, 560, 567, 571, 574, 653,

D6/672, 682, 682.2

CPC ... A47B 96/027; A47B 61/003; A47B 57/585;

A47B 96/02
